Primary Examiner—Ian Simmons*Assistant Examiner*—Melanie Levy(74) *Attorney, Agent, or Firm*—Brij K. Agarwal; Eckert Seamans Cherin & Mellott, LLC(57) **CLAIM**

The ornamental design for a changing room, as shown and described.

DESCRIPTION

FIG. 1 is a front perspective view of a changing room showing my new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof; and,

FIG. 7 is a bottom plan view thereof.

The broken lines shown in the drawings are for illustrative purposes only and form no part of the claimed design.
